Office Action dated Apr. 27, 2022 in Taiwanese Application No. 110305021.

Primary Examiner — Katherine Glennon*Assistant Examiner* — Molly Loch(74) *Attorney, Agent, or Firm* — Sughrue Mion, PLLC(57) **CLAIM**

The ornamental design for a watch bezel, as shown and described.

DESCRIPTION

FIG. 1 is a perspective view of the watch bezel according to my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The features shown in broken lines form no part of the claimed design.
